CLAIM

The ornamental design for a rebar chair with depth gauge, as shown and described.

DESCRIPTION

FIG. 1 is a perspective view showing the front, top and right sides of a rebar chair with depth gauge in accordance with the new design;

FIG. 2 is a top plan view thereof;

FIG. 3 is a left side elevation view thereof;

FIG. 4 is a front side elevation view thereof, the rear elevation being a mirror image of the front side as shown;

FIG. 5 is a left side elevation view thereof; and,

FIG. 6 is a bottom plan view thereof.
